UNITED STATES PATENT OFFICE.

WELCOME P. GAMMONS, JR., OF NEW YORK, N. Y.

MACHINE FOR SEWING SWEAT-BANDS INTO HATS.

SPECIFICATION forming part of Letters Patent No. 519,038, dated May 1, 1894.

Application filed June 3, 1892. Serial No. 435,436. (No model.)

To all whom it may concern:

Be it known that I, WELCOME P. GAMMONS, Jr., a citizen of the United States, residing at New York city, in the county of New York and State of New York, have invented certain new and useful Improvements in Machines for Sewing Sweat-Bands into Hats; and I do declare the following to be a full, clear, and exact description of the invention, such as will enable others skilled in the art to which it appertains to make and use the same.

My invention has relation to improvements in machines for sewing sweat bands into hats, and it has for its primary object to provide a machine adapted with slight alterations or modifications to form either the zigzag or over-seam or whip stitch disclosed in my prior application for patent filed May 31, 1892, Serial No. 434,976, patented June 28, 1892, No. 477,751; my present invention being designed more particularly as an improvement upon the machine disclosed in my application for patent filed May 27, 1891, Serial No. 394,301, patented June 28, 1892, No. 477,750, which is adapted to be used for sewing sweat bands or linings into hats and caps so that the stitch will cover one edge of the band and serve as a finish while securing the band to the folded edge of the hat body. With the foregoing and other objects in view, the novelty in my present invention will be fully understood from the following description and claims when taken in conjunction with the accompanying drawings, in which—

Figure 1, is an elevation of one side of my improved machine. Fig. 2, is an elevation of the opposite side of the same with the covering plate of the overhanging or fixed arm removed, to show the interior mechanism thereof. Fig. 3, is a front elevation of the machine. Fig. 4, is an inverted plan view with the platform hanger, the feed and clamp wheels, and the guide removed. Fig. 5, is a horizontal section taken in the plane indicated by the line x, x , of Fig. 2, looking downwardly. Fig. 6, is a detail elevation of the cam for raising and lowering the needle frame, the gudgeon of said frame being illustrated in position. Fig. 7, is a detail perspective view of the loop-taker, its rock shaft and pin-

ion, and the rack bar for rocking said shaft, and Fig. 8 is a perspective view of the material guide removed.

In said drawings similar letters designate corresponding parts throughout the several views, referring to which—

A, indicates the base; B, the overhanging or fixed arm, and C, the drive shaft which is journaled in the fixed arm, as better shown in Fig. 2, of the drawings. This drive shaft C, is provided in alignment with the hollow standard of the fixed or overhanging arm, with a disk D, having the peripheral cam groove a , which engages the lug b , carried at the upper end of the lever E, and serves to impart a rocking motion to said lever for a purpose presently described. The lever E, which takes through a slot in the base A, as shown, has its lower end loosely connected to one end of the horizontal lever F, which is fulcrumed at an intermediate point in its length and is provided with a longitudinal slot c , for the adjustable connection of the pitman G, which connection is effected by the screw d , which takes through the slot c , an eye in the pitman, and a transverse slot in the base plate; and the nut e , which is mounted upon the upper end of the screw as shown. This pitman G, is connected at its forward end to a short lever H, which carries a spring pressed pawl I, engaging with the ratchet wheel J, fixed upon the vertical shaft f , of the horizontally disposed feed wheel K, which feed wheel is designed to be moved a slight distance through the medium of the mechanism just described, to feed the materials while the vertically slideable frame is in its upper position, and at the beginning of the outward stroke of the needle so that the needle will take through the sweat band and the folded edge of the hat to form the next stitch at the proper distance from the first stitch or passage of the needle through the sweat band and hat, for a purpose more fully hereinafter described.

L, indicates a clamping wheel which is pivotally mounted upon a bowed bracket arm g , which is preferably formed integral with a slotted plate h , held in position upon the base A, by a screw as i , and which plate is designed to be moved by the cam lever M, away

from the feed wheel K, so as to permit of the interposition of the materials between the same; the clamping wheel L, normally pressing toward the feed wheel K, or the materials 5 between the two, by virtue of the retracting spring j, which is connected at one end to a lug depending from the plate H, and its opposite end to a stud or the like depending from the base A.

- 10 To support the materials properly while the same are clamped and are being fed, through the medium of the mechanism described, I have provided a slotted hanger N, which is suitably connected to the forward end of the base A, and is designed to support the horizontal platform P. This platform P, upon which the hat is designed to rest, is provided at its inner end with a fixed bracket plate m, which is provided upon its inner side with a 20 vertical rib designed to rest and move in the vertical slot of the hanger N, upon which the bracket plate is adjustably fixed by the binding screw n, the shank of which takes through the slot of the hanger N, and into the rib of the bracket m, whereby it will be seen that the platform P, may be fixed at various elevations to suit hats of various styles and sizes.

R, indicates the material guide. This guide 30 may be of any approved form and construction, but it is preferably constructed as shown in Fig. 8, and is of a right-angle form in cross-section above and on one side of the feed wheel K, and merges into a vertically disposed plate upon the opposite side of the said wheel which extends through a recess or opening p, formed in the vertical portion of the guide as better shown in Fig. 3, of the drawings. The guide R, is provided at one end with a short 35 vertical slot r, through which takes the screw s, which takes into the vertical portion of the bracket arm t, which rests in a recess formed in the inner side of the guide and is suitably connected to the base A, as shown. The 40 guide R, is also provided upon its inner side adjacent to its opposite end where it is of an angular form in cross section, with a recess similar to the one adjacent to its opposite end, in which rests the vertical, slotted portion of the bracket arm n', through which 45 takes the set screw v, which takes into a threaded aperture in the guide R. By this manner of connecting the guide R, to the base, it will be perceived that the said guide 50 may be adjusted vertically to a slight extent, and may be readily removed and replaced by another guide when desirable; the present guide being adapted more especially for attaching sweat bands to soft hats in which no 55 reed is used and in which one edge of the sweat band is finished by the thread as will be presently described. The forward edge of the horizontal portion of the guide R, is recessed as shown so that it describes a right 60 hand curve; and connected to the said curved edge by a screw or the like is a curvilinear

plate S, which depends a slight distance below the under side of the horizontal portion of the guide and is designed to serve in conjunction with the said horizontal portion and the vertical portion of the guide, to lead the material between the wheels K, and L. This plate S, is notched in its lower side at a proper point as shown to permit the passage of the needle. 70

Mounted in suitable ways in the face of the overhanging or fixed arm B, is the vertically 80 slideable frame T, which is provided upon its inner side at a point adjacent to its upper end with an anti-friction lug U, designed to move in the cam groove w, of the wheel or disk V, which wheel or disk is fixed upon the outer end of the drive shaft C, whereby it will be seen that at each rotation of the said shaft, the frame T, and its appurtenances will be lowered and raised; such movement of the frame T, being properly timed with respect to the movements of the other parts as will be presently pointed out. 85

Journalized in a bracket a', extending forwardly from the movable frame T, is a rock shaft b', upon one end of which is fixed the swinging arm A', of the rocking or reciprocating needle B', which is preferably connected in a detachable and adjustable manner to the said arm A', by a set screw or the like. 90

Fixed at a suitable point upon the drive shaft C, is a beveled gear wheel d', which meshes with a pinion e', upon a short transverse shaft f', which extends through the wall of the overhanging or fixed arm B, and carries a disk g', at its outer end to which is eccentrically connected one end of a pitman h', which pitman is connected at its forward end 100 to a crank arm C', fixed upon the end of the shaft b', opposite to that which the arm A', is connected, whereby it will be seen that when the drive shaft is rotated the needle B', will be rocked or reciprocated. The crank 105 arm C', is provided at its upper end with an approximately T-shaped head D', in which is formed a cam slot k', designed to impart a vertically reciprocatory movement to a rack bar E', through the medium of the crank pin 110 F', carried by the said rack bar E', which rack bar meshes with a pinion l', upon one end of the shaft n', of the loop taker M', which 115 shaft is journaled in the frame T. It will be seen that upon the inward stroke of the needle, the rack bar E', is given an upward movement, which bar, through the medium of the pinion on the loop-taker shaft, gives said shaft a slight rocking motion so as to vibrate the loop taker and raise its point to a plane 120 above the path of the needle. Upon the downward stroke of the rack bar E', and during the receding stroke of the needle, the loop taker will rock inwardly to take the thread loop from the needle, and upon the succeeding upper stroke of the rack bar, the loop taker 125 will rock outwardly or in a reverse direction. 130

rection, into its position above the path of the needle ready to rock inward to shed its first loop and take another loop from the needle, as will be hereinafter more clearly pointed out.

The rock shaft n' , is provided at one end with a sleeve socket p' , as shown in which the shank of the loop taker is removably secured by a set screw or the like; and the pinion l' , upon the said shaft n' , is preferably provided with a sleeve or collar extension m' , through which takes a set screw to fix the pinion upon the shaft, whereby it will be readily perceived that the loop taker and its shaft may be readily adjusted with respect to the rack bar E' .

The mechanism of my improved machine is so timed that when the vertically slidable frame T , is moving up or down, the crank pin F' , of the rack bar E' , is at the forward end of the cam slot k' , of the crank arm C' , by reason of which the said crank arm C' , will have a lost motion and the rack bar E' , and the needle arm A' , will be held stationary with respect to the slidable frame T , during the greater part of the upward and downward movements of the said frame.

Although the rack bar E' , and the loop taker M' , actuated thereby together with the needle arm A' , and the needle carried thereby, do not move materially during the movements of the vertically slidable frame, yet when the said slidable frame is in its lower position, the said parts will be thrown into action and the needle will take through the material, and the loop taker will take a loop from the needle; and after the slidable frame has attained its upper position, the needle and loop taker will again be thrown into action and the needle will pass over the material, and the loop taker will shed its first loop, and take another loop from the needle and will draw it through the first loop or the loop that it has just shed, or in other words a stitch will be formed while the frame T , is in its lower position, and another stitch will be formed when the said frame is in its upper position; the first stitch being through the materials and the next stitch over the same.

Suitably connected to the front of the vertically slidable frame T at the lower end thereof, is the needle plate W' , which is provided with a reduced depending portion as shown, which has an eye adjacent to its lower end for the passage of the needle.

X' , indicates the former for the material, which is suitably connected to the bracket m , and is designed to be adjusted vertically, so that the needle will properly take through the sweat band and the folded edge of the hat.

In operation the folded edge of the hat and the sweat band are placed within the former and between the clamping wheel L , and the feed wheel K , and the said clamping wheel is brought in against the same by manipulating

the cam lever M . The machine is then started, when the needle will take through the sweat band and the folded edge of the hat, and upon the receding stroke of the needle, the loop taker will take a loop from the needle. The vertically slidable frame will then be raised to its upper position, after which the needle will pass over the sweat band and the folded edge of the hat to finish the edge of the former; and upon the receding stroke of the needle in its upper position, the loop taker will shed its first loop and will take a loop from the needle and draw it through the first loop, and during the receding stroke of the needle while the frame T , is in its upper position, the feed wheel K , will be actuated to move the materials, which movement will draw the loop that has just been shed tight across the sweat band and the folded edge of the hat, whereby the overseam whip stitch described in my prior application above referred to, will be formed. At the completion of the receding stroke of the needle in its upper position, the slidable frame will move downwardly and the operation before described will be repeated.

In the practice of my invention I will not confine myself to the specific construction and relative arrangement of the several parts of my machine, as I reserve the right to make such modifications as fairly fall within the scope of my invention.

Having described my invention, what I claim is—

1. In a sewing machine an organized, stitch-forming mechanism, and a vertical rectilinearly sliding frame carrying the same, the said mechanism being adapted to form a stitch at the termination of each downward and upward movement respectively of the frame, substantially as specified.

2. In a sewing machine a vertically and linearly reciprocating organized stitch-forming mechanism, comprising a rocking or reciprocating needle and a loop-taker having its point directed away from the needle and the path of the materials, and a suitable means for raising and lowering the same so that the needle will take alternately through the material to be united and over the same, substantially as and for the purpose set forth.

3. In a sewing machine, the combination with a vertical rectilinearly sliding frame, and an organized stitch forming mechanism carried thereby; of a cam arranged in a plane parallel with that of the sliding frame adapted to raise and lower the same, and a suitable means for rotating the cam, substantially as specified.

4. In a sewing machine, a rotary feed wheel adapted to impinge upon the material operated upon, and a drive shaft, in combination with a vertical, rectilinearly sliding frame, a stitch forming mechanism carried by said frame, and comprising a needle and a loop taker directed away from the needle, and mechanism

intermediate the drive shaft, and the sliding frame, needle, loop-taker, and feed wheel, adapted to raise and lower the frame, and actuate the needle, the loop-taker and the feed wheel, substantially as specified.

5. In a sewing machine, the combination with a needle carrying arm fixed upon a rock shaft and carrying the needle, a crank arm also fixed upon the rock shaft and carrying a cam, 10 and a suitable means for oscillating the crank arm, of a loop taker fixed on a rock shaft, a pinion also fixed on said rock shaft, and a rack bar engaging the said pinion and having a lug in engagement with the cam on the crank arm, substantially as and for the purpose set forth.

6. In a sewing machine, substantially as described, the combination with a feed wheel mounted upon a vertical shaft, and a ratchet 20 wheel also mounted on said shaft, of a drive shaft, a disk mounted on said shaft and having a cam groove, a lever fulcrumed at an intermediate point in its length and having a lug entering the cam groove of the disk on the drive shaft, the longitudinally slotted lever F connected to the first named lever, a lever fulcrumed adjacent to the vertical shaft and carrying a spring-pressed pawl engaging the ratchet wheel, a pitman connected at one 30 end to the lever carrying the pawl, and a screw adjustably connecting the opposite end of said lever and the slotted lever F, substantially as and for the purpose, set forth.

7. In a sewing machine, a vertical rectilinearly sliding frame, a rocking or reciprocatory needle carried by said frame, a rocking loop-taker also carried by the vertically sliding frame and directed away from the needle, and means for intermittently raising and lowering the vertically sliding frame in a rectilinear plane, and for actuating the needle and the loop taker while the sliding frame is at rest in its upper and lower positions, substantially as specified.

45 8. In a sewing machine, substantially as described, the combination with the base having parallel guides upon its upper side, and a feeding mechanism carried by the base; of the sliding plate h, arranged between the 50 guides of the base and having a longitudinal slot, a screw taking through said slot and into the base, a clamping wheel carried by an arm of the sliding plate, a spring connected to the sliding plate and to the base, and the lever M, 55 having the eccentrically mounted head at one

end adapted to engage the sliding plate, all substantially as and for the purpose set forth.

9. In a sewing machine, substantially as described, the combination with the base, an organized stitch forming mechanism mounted 60 thereon, a material guide connected to the base, and a slotted hanger depending from the base; of a platform, a bracket connected to the platform and having a rib to take into the slot of the hanger, and a set screw taking through the slot of the hanger and into the bracket, substantially as and for the purpose set forth.

10. In a sewing machine, the combination with a base, an overhanging and fixed arm 70 mounted on the base, and the drive shaft journaled in said arm and having a cam at its forward end; of a vertical, rectilinearly, slidable frame adapted to be raised and lowered by the cam on the drive shaft, a needle 75 journaled in the slidable frame and carrying the needle, a crank arm also fixed upon the rock shaft and carrying a cam, a loop taker fixed on a rock shaft carried by the slidable frame, 80 a pinion also fixed on said rock shaft, a rack bar engaging the said pinion and having a lug in engagement with the cam on the crank arm, and mechanism intermediate of the drive shaft and the crank arm adapted to impart 85 an oscillatory movement to the latter, substantially as specified.

11. In a sewing machine, the combination with a base, an overhanging and fixed arm mounted on the base, and a drive shaft journaled in the overhanging and fixed arm; of a vertical, rectilinearly slidable frame mounted in ways in the face of the fixed arm, a needle carrying arm fixed upon a rock shaft journaled in the slidable frame and carrying a 90 needle, a loop taker fixed upon a rock shaft journaled in the slidable frame, mechanism intermediate the drive shaft and the slidable frame adapted to raise and lower the same, and mechanism intermediate of the drive 95 shaft and rock shafts carrying the needle carrying arm and the loop taker, respectively, adapted to rock said shafts, substantially as specified.

In testimony whereof I affix my signature in 105 presence of two witnesses.
